Primary Examiner — T. Chase Nelson(74) *Attorney, Agent, or Firm* — Marshall A. Lerner, Esq.; Marvin H. Kleinberg, Esq.; Kleinberg & Lerner, LLP(57) **CLAIM**

The ornamental design for a shoe bottom, as shown and described.

DESCRIPTION

FIG. 1 is a perspective view of an exemplary embodiment of a shoe bottom in accordance with my new design.

FIG. 2 is a bottom plan view thereof;

FIG. 3 is a left side view thereof;

FIG. 4 is a right side view thereof;

FIG. 5 is a rear elevation view thereof;

FIG. 6 is a front elevation view thereof; and,

FIG. 7 is a top plan view thereof.

Broken lines showing the remainder of the shoe in the figures are for illustrative purposes only and form no part of the claimed invention.
